UNITED STATES PATENT OFFICE

119,661

DESIGN FOR A METALLIC SEALING STRIP

Earl R. Rehfeld, Chicago, Ill.

Application January 31, 1940, Serial No. 89,901

Term of patent 14 years

To all whom it may concern:

Be it known that I, Earl R. Rehfeld, a citizen of the United States, residing at 3416 North Kolmar Avenue, in the county of Cook and State of Illinois, have invented a new, original, and ornamental Design for a Metallic Sealing Strip, of which the following is a specification, reference being had to the accompanying drawing, forming a part thereof, in which:

Figure 1 is a plan view of a metallic sealing strip, the parts shown in broken lines being merely repeats of the parts shown in full lines; and Figure 2 is a side view of the showing in Figure 1, both views showing my new design.

I claim:

The ornamental design for a metallic sealing strip, substantially as shown and described.

EARL R. REHFELD.
